UNITED STATES PATENT OFFICE.

RALEIGH B. BUZZAIRD, OF WASHINGTON, DISTRICT OF COLUMBIA, ASSIGNOR, BY
MESNE ASSIGNMENTS, TO DAVIS AUTOMATIC EQUIPMENT CORPORATION, OF
NEW YORK, N. Y., A CORPORATION OF NEW YORK.

LOCKER.

1,391,044.

Specification of Letters Patent. Patented Sept. 20, 1921.

Application filed July 17, 1920. Serial No. 397,121.

To all whom it may concern:

Be it known that I, RALEIGH B. BUZZAIRD, a citizen of the United States, and resident of Washington, in the District of Columbia, 5 have invented a new and useful Locker, of which the following is a specification.

The object of the invention is to provide certain improvements in public coin-controlled lockers, wherein articles can be 10 checked and locked upon the deposit of a coin. To this end the invention may be said to comprise the parts, improvements and combinations hereinafter described in preferred embodiment, and more particularly pointed out in the appended claims.

In the accompanying drawings forming a part hereof:

Figure 1 is a fragmentary front elevation of the frame member of the locker structure 20 which carries the locks, showing the openings for the top door lock and for the control lock at the bottom, with all the region between broken out.

Fig. 2 is a fragmentary vertical section on the line 2—2 of Fig. 1, showing one of the door locks and the control lock in place.

Fig. 3 is a fragmentary vertical section on the line 3—3 of Fig. 1, showing one of the door locks in place, in its relation to the coin 30 chute.

Fig. 4 is a side elevation of the frame member, with portions broken out at different elevations, showing three of the catches for retaining the door locks, and with the 35 control rod raised and pushed back on the coin chute, in the position which it would occupy preparatory to withdrawing the chute and rod from the casing. A lesser raising than this of the control rod is sufficient to release the catches of the door locks, 40 to permit the latter to be taken out.

Fig. 5 is a front elevation on a small scale of a single row locker, an intermediate portion being broken out.

Fig. 6 is a horizontal section on the line 45 6—6 of Fig. 4.

Fig. 7 is a horizontal section on the line 7—7 of Fig. 5.

The lockers 1 are built in a multiple structure comprising one or more vertical rows of locker compartments. Each locker or locker compartment has a door 2, which can be locked by a coin lock 3 in the vertical frame member 4 extending along the free edges of

the door-openings of all the compartments 55 of the vertical row. There is consequently a vertical row of locks corresponding to each vertical row of compartments. The mechanism of each of the locks is carried by a front plate or escutcheon 5, which occupies 60 an opening 6 in the frame member, the plate having rearwardly projecting flanges 7, 8, 9 at the top and sides entering the opening, and a downward projection 10 at the bottom which hooks behind the bottom of the opening.

The top flange 7 of each lock plate has a slot 11 which receives a vertically sliding catch 12, mounted in a suitable guide 13 on the back of the front wall of said frame member, and having a knob 14 which projects outwardly through a slot 15. There is one of these catches for each of the locks, and the several catches are independent of each other, so that any one of the locks can 75 be taken out without freeing the others. Heretofore it has been the practice to hold the locks in place by a series of catches secured upon a common control rod, so that in order to remove one of the locks it was 80 necessary to release all of them, with the result that one or more of the others were likely to fall out. This was not only inconvenient, but in replacing the locks they were likely to become mixed, so that a patron 85 sometimes found that his key would not unlock the compartment where he had left his possessions, or would give him access to a compartment which he was not entitled to open. Also, upon occasion, one of the 90 catches would become loose on the control rod and drop down, giving rise to serious difficulty.

According to this invention the individual, 95 independently operable catches 12 are separate from a common vertical control rod or bar 16, which is contained within the frame member and has a series of downwardly facing shoulders 17 which normally overlie the catches and prevent them being raised sufficiently to free the locks, as long as the control rod is held down.

The locks themselves may be any one of a variety of suitable or known kinds. Each has a bolt 18 which operates through a slot 19 in the side flange 8 and a registering slot 105 in the door-opening side wall of the frame member 4, to engage a keeper on the door.

A coin-entrance 20 in the plate 5 admits the coin to mechanism in the lock whereby the bolt can be projected to lock the door, as by turning a knob or key,—in the particular lock represented by turning a knob 21. The key 22 is normally confined in the lock, and can be removed when the bolt is projected, to serve as the patron's check, which enables him to unlock the locker when he desires to 10 take out his belongings. As the particular mechanism of the lock is not involved in this invention, special illustration thereof is unnecessary.

The coins from the several locks are delivered from rearwardly inclined chute lips 23 at the bottoms thereof to entrance openings 24 in the front wall of a coin chute 25 extending vertically in the interior of the frame member throughout the length thereof, and delivering into a coin receptacle (not shown) in the lower part of the structure. Said chute is removable through an opening in the top of the locker structure, where it is provided with a handle 26 for the purpose, 20 and is held against displacement in any transverse or horizontal direction by bearing against the side and front and back walls of the hollow frame member. Thus, the back of the coin chute may rest against a fixed 25 back wall 27, and a side flange 28 on the chute (suitably cut away for the passage of the bolts 18) may project into bearing relation to the fixed front wall; while, laterally, the chute is in bearing relation to the inner 30 side wall 29 and has brackets 30 on its other side extending to the outer side wall.

Said brackets 30 fixed on the coin chute have vertical slotted openings 31 in their forward portions in which the control rod 16 40 is laterally sustained, and vertically guided so as to be capable of movement relatively to the chute.

The control rod is normally positively held in its downward position, opposing 45 raising of any of the catches 12, by a two-armed lever 32 connected to the lower part of the control rod by a pivot 33. The body of the lever is disposed vertically, and its upper arm has a rearwardly projecting, 50 rounded-end nose 34, which projects over the top of one of the brackets 30, to fulcrum thereon when the lower end of the lever is pulled forward, thereby raising the rod relatively to the chute. A transversely projecting handle 35 on the lower end of the lever is provided for pulling it forward.

The same handle 35 preferably also serves as an abutment whereby the control rod, and thereby the coin-chute, are locked against 60 vertical withdrawal movement, by means of a lock 36 which occupies an opening 37 in the lower part of the frame member. This lock comprises a suitable front plate, having

a portion 38 which hooks under one edge of said opening, and carrying a key lock mechanism 39, the bolt of which can be projected under another edge of the opening. A rearward projection 41 on the plate overhangs the handle 35, and thereby prevents upward movement thereof when the lock is in place. 70 This lock, therefore, commands the control rod, normally preventing it from being lifted so as to release the door locks, and also locks both the coin chute and the control rod against withdrawal from the locker structure. 75 When the lock 36 is opened, or removed, the control rod can be lifted by its lever to free the separate lock catches 12, or the coin chute and control rod assemblage can be withdrawn through the top of the 80 structure by pulling on the handle 26.

In order thus to remove the chute and rod, the rod must first be moved upward a distance on the chute and backward, so that its forwardly projecting portions may clear the 85 catches 12 when the assemblage is lifted out. For this purpose the back of the control rod is notched or recessed at intervals, as indicated at 40.

What I claim as new is:

1. In a locker, the combination with a structure forming a vertical row of compartments with doors, and locks for said doors mounted removably in the frame of the structure at one side of the door openings, of individual catches in the frame for holding said locks in place, a common rod separate from the catches for holding and releasing the same, and a lock controlling said rod.

2. In a locker, the combination with a structure forming a vertical row of compartments with doors, and locks for said doors mounted removably in the frame of the structure at one side of the door openings, of individual catches in the frame for holding said locks in place, a common rod separate from the catches for holding and releasing the same, a lever for raising said rod, the frame having an opening giving access to said lever, and a lock and closure commanding said opening and locking said rod against releasing movement.

3. In a locker, the combination with a structure forming a vertical row of compartments with doors, and locks for said doors mounted removably in the frame of the structure at one side of the door openings, of individual catches in the frame for holding said locks in place, a common rod separate from the catches for holding and releasing the same, a lever on the rod for raising the same, and a lock and closure commanding said opening and coöperating with said lever to lock the rod against releasing movement.

RALEIGH B. BUZZAIRD,
